Patented Oct. 21, 1969

215,642

CHILD'S ONE-PIECE GARMENT

Lavinia G. Lofgren, 457 Orchard Ave.,
Battle Creek, Mich. 49017

Filed July 5, 1968, Ser. No. 12,630

Term of patent 14 years

Int. Cl. D2—02

U.S. Cl. D2—33

FIG. 1

FIG. 2

FIG. 3

FIG. 4

FIG. 1 is an outside plan view of a child's one-piece garment showing my new design;

FIG. 2 is an inside plan view thereof;

FIG. 3 is a front elevational view of the child's one-piece garment shown in wearing position on a reduced scale; and

FIG. 4 is a rear elevational view thereof on a reduced scale.

I claim:

The ornamental design for a child's one-piece garment, substantially as shown.
